ADDISON B. CARLL, OF NEW YORK, N. Y.

CHAIN PIPE WRENCH.

1,410,993.

Specification of Letters Patent. Patented Mar. 28, 1922.

Application filed May 18, 1921. Serial No. 470,718.

To all whom it may concern:

Be it known that I, ADDISON B. CARLL, a citizen of the United States, residing at New York, in the county of New York and State 5 of New York, have invented a new and useful Chain Pipe Wrench, of which the following is a specification.

This invention relates to pipe wrenches, and more particularly to that class in which 10 a chain is employed to surround the pipe to secure a hold thereupon.

The object is to provide a wrench of this character by means of which pipes may be turned in either direction without reversing the wrench, and in which the same firm grip upon the pipe is obtained in either case, the wrench being applied to said pipe in what may be termed an intermediate position, whether it be desired to turn it in one 15 direction or in the other, after which, by a simple longitudinal movement of the wrench transversely of the pipe, it may be caused to engage the latter for turning in the desired direction.

Another object is to provide a chain pipe wrench so formed and proportioned as to insure a powerful gripping action upon the pipe when the operating handle of the wrench is turned in either direction, the entire leverage of the handle plus the engaging head being utilized to turn the pipe, while the tendency to rock the engaging head while the handle or lever is under strain, only results in binding the chain in 30 tighter engagement with the pipe, thus preventing any accidental slipping of the chain around the pipe.

A further object is to provide a wrench having a permanently attached chain which, 40 after the engaging head is applied to the pipe, may be easily passed around the latter and quickly attached in operative position, whether the pipe be of maximum or minimum size, the ready adjustability of the 45 chain aiding in easily detaching the wrench when the operation is completed.

A still further object is to provide a chain pipe wrench which may be readily used to 50 screw or unscrew fittings of various kinds, as well as short nipples and elbows, in which, generally, there is little exposed surface upon which an ordinary wrench may

be applied, the device of the present invention being relatively narrow and having means for engagement with such fittings 55 and being of simple, though rugged, construction, composed of few parts and capable of manufacture and sale at a low cost.

A full and complete understanding of the invention may be obtained from a consideration of the following detailed description, 60 taken in connection with the accompanying drawing forming a part of this specification, it being understood that while the drawing shows a practical form of the invention, the latter is not confined to strict 65 conformity therewith, but may be changed or modified, so long as such changes or modifications mark no material departure from the salient features of the invention as specifically pointed out in the appended claims.

In the drawing, in which similar reference characters designate corresponding parts throughout the several figures:

Fig. 1 is a side elevation of the improved 75 wrench, the operating handle being partly broken off and showing, in full lines, the position of the pipe and chain for turning in one direction, and in dotted lines for turning in the opposite direction.

Fig. 2 is a plan view of the same.

Fig. 3 is a detail longitudinal section of the wrench head and removable shoe.

Fig. 4 is a bottom plan view of the removable shoe.

Fig. 5 is a detail longitudinal sectional view of a slightly modified form of removable or reversible shoe, the wrench head being shown in dotted lines.

A substantially triangular-shaped head 90 1, preferably formed of forged steel, is provided, said head being relatively long as compared to its thickness, the top comprising two inclined surfaces 2 rising to an apex 3 located at the center of the head, thus 95 giving the head the greatest thickness at the center thereof, where the greatest strength is required to withstand the strain to which the head is subjected during the operation of the wrench.

The triangular block forming the head is of a width substantially equal to the height of the triangular sides thereof, as 100 illustrated in Fig. 2 of the drawing, and

at the ends where the inclined upper faces 2 approach the straight under side 4 of the head, the latter is symmetrically curved as at 5 and 6 respectively to provide what 5 may be termed the heel and the toe of the head block.

An operating handle 7 preferably formed integrally with the head 1 and having its longitudinal axis arranged substantially 10 parallel to and above the straight horizontal bottom face 4 of the head, is joined to the inclined upper face 2 of the head, which extends between the apex 3 and the heel 5, by an inclined portion 8.

15 The handle 7 is preferably narrower than the width of the head, and is rounded or of the oval shape in cross section to facilitate the grasping of the handle by the operator, and the inclined portion 8, where connected to 20 the head, extends nearly the full length of the adjacent upper inclined face 2, the outer face of the inclined portion 8 merging with the apex 3.

Extending outwardly from the heel 5 and 25 joined to the lower face of the operating handle, at the inclined portion 8 thereof, is an integral ear 9, located at the longitudinal center of the handle and the head, and provided with a suitable aperture for the reception of a rivet or pin 10, which connects the 30 terminal pair of links of a chain 11 permanently thereto and permits the latter to freely swing on the same.

The chain 11 comprises a plurality of links 35 of ordinary construction, arranged in pairs, joined together by rivets, having their ends extended beyond the outer faces of the outside links to provide oppositely disposed studs 12, any pair of which is adapted to be 40 engaged with and held by a pair of spaced, rearwardly-directed hooks 13, formed at the upper ends of spaced upwardly extending lugs 14 cast integrally with the head, and having their side walls flush with the side 45 walls of the head. The upper walls of the lugs 14 are horizontally disposed and extend from the apex 3 to the seat of the hooks 13, and provide for freely sliding the studs 12 of the chain into their seated position, as will 50 be readily understood. The space between the lugs 14 is sufficient to freely permit the placing of the outermost links of the chain between the same, and the forward edges of said lugs are so formed as to allow the 55 adjacent links of the chain to rest upon the forward inclined face 2 extending from the apex 3 to the toe end 6 of the head.

The several links of the chain are so proportioned and shaped as to fit snugly around 60 the rounded toe end 6 of the head, no matter which pair of studs 12 may be engaged with the spaced hooks 13, when the wrench is in the applied position indicated in dotted lines in Fig. 1, and it will also be seen 65 that the terminal pair of links of the chain,

where connected to the ear 9, are also adapted to snugly fit around the heel end 5 of the head, when the wrench is in the applied position indicated in full lines in said figure.

The lower face 4 of the head 1 is provided 70 with a transversely disposed groove 15 extending entirely across the same, and is further provided with a centrally disposed threaded aperture 16 extending part way through the head in a direction toward the 75 apex 3.

The side walls of the groove or recess 15 are somewhat tapered to correspond with the side edges of a centrally disposed boss 17, formed integrally with a removable shoe 80 18, the latter being co-extensive with the length of the head and adapted to fit against the bottom face of the same, with the boss 16 fitting within the groove 15, and held in its engagement therewith by a suitable screw 85 19 having its head countersunk in a transverse, centrally located recess 20 formed in the lower face of the removable shoe 18, as clearly shown in Fig. 3 of the drawing.

The shoe 18 is rigidly held in position 90 against the lower face of the head by means of the screw 19, and the transverse boss 17 fitting within the recess of the head, effectively prevents the endwise movement of the shoe.

The lower surface of the shoe 18 is rounded from the spaced walls of the recess 20 to the ends thereof, where they are rounded to coincide with the curved ends of the head comprising the heel and toe, and transversely 100 disposed teeth 21 are formed in said curved walls and in opposite relation to each other to provide arcuate oppositely-disposed pipe gripping surfaces for engaging the pipe to be turned and to prevent slipping of the 105 wrench thereon. Instead of a removable shoe, the pipe gripping teeth could be cut in the underside of the head.

The full line position illustrated in Fig. 1 shows what may be called the toe bite or 110 hold of the wrench, which position is assumed by the wrench when turning the pipe in one direction, as for unscrewing the same from threaded connection with another member.

The dotted line position of said figure indicates what may be termed the heel bite or hold of the wrench, and indicates the position assumed by the wrench when turning the pipe in the opposite direction, as to 12 screw the same into engagement.

The head of the wrench is placed centrally upon the pipe or against the same, as the case may be, with the recess 20 fitting the same when the chain is drawn around the 12 pipe and the proper link connected with the hooks 14. By drawing the head to one side to engage the teeth 21 at the toe end of the shoe with the pipe and exerting an upward pressure on the handle 7, the chain will be 13

caused to bind against the pipe with a powerful grip. By manipulating the head and the chain in the opposite manner, the teeth at the heel end will suffice to bind the chain 5 for turning the pipe in the opposite direction. The head and shoe which together forms the jaw for the wrench, acts as an elliptical cam in tightening the chain, whichever way the wrench is turned. It will be 10 observed from Fig. 1 that the handle is offset from the head and shoe so as to give free use of the heel of the wrench upon the pipe.

In Figure 5 a reversible shoe 22 is shown, having teeth 23 on both faces thereof, and a central threaded aperture 24 for the reception of a fastening screw. In this form, the head is provided with a toothed seat for the reception of that set of teeth not in use, and the head of the screw is seated in a 20 countersunk seat in said head, and when one set of teeth becomes materially worn, it is only necessary to loosen the screw and reverse the shoe to present a new set of teeth for use.

25 From the foregoing description it will be seen that a simple, cheaply manufactured wrench has been provided, consisting of few parts, so formed and associated, as to produce a powerful gripping action upon the 30 pipe or other object to be turned.

What is claimed is:—

1. In a chain pipe wrench, the combination of a head having curved oppositely disposed pipe gripping faces on its underside extending from substantially the center thereof lengthwise toward each end, the rounded ends of the said gripping faces merging with the rounded ends of said head so as to provide symmetrical chain-bearing 40 ends, a handle at one end of the head rising from that face of the head remote from the gripping face and offset from the adjacent chain bearing end, a chain, means for pivotally attaching one end of said chain to the 45 underside of the handle above the chain-bearing end, and means for attaching the other end of said chain to the upper or outer side of the head above the other chain-bearing end, whereby the head acts as an elliptical cam causing the chain to wrap around either end of the head and the chain swinging clear of the other end and being drawn more firmly around the pipe.

2. In a pipe wrench, the combination of a 55 head having rounded chain bearing ends, and curved oppositely disposed toothed pipe gripping surfaces on its under side, said toothed surfaces extending from the central part to each end and merging with the 60 rounded chain bearing ends, a handle joined to the head at one end at a point above the chain bearing end, a chain having one end pivotally attached adjacent to but above the inner rounded end of the head, and means 65 for attaching the chain to the opposite end

of the head above the outer chain bearing end, whereby the chain will wrap around either end of the head and at the same time will swing clear of the other end and be drawn more firmly around the pipe. 70

3. In a chain pipe wrench, the combination of a head having its upper side tapered from its center lengthwise toward each end, and its under side provided with a transverse recess in the center, a handle joining 75 one of the tapered upper faces and offset from the head, a shoe mounted upon the underside of the head, said shoe having oppositely disposed arcuate pipe gripping surfaces each side of its central part and 80 rounded chain bearing ends, said central part having a recess on the under side and a shouldered rib on the upper side to engage the recess of the head, means for holding said shoe to the head, a chain pivotally attached adjacent to but above the handle end of head, and adjustable chain attaching means in relatively the same position on the opposite end of the head, whereby either end of the shoe may be used upon the pipe, 85 the chain at one end swinging clear of the shoe reaching round the pipe and being tightened by the action of the opposite end of the shoe and head against it.

4. In a pipe wrench, comprising a head, 90 handle and chain, a pipe gripping shoe on the underside of the head extending an equal distance from the center of the head toward each end, the underside of said shoe having pipe gripping teeth and being curved or 100 arcuate each way from the center so as to rock upon the pipe and to engage it from either end of the shoe, the handle of the wrench being so joined to the head as to give free action of either end of the shoe, a 105 chain having one end fastened to the handle end of the head and arranged to extend around each end of said shoe, and means for adjustably attaching the other end of the chain to the opposite end of the head in the 110 same relative position with regard to the shoe as at the fixed end, whereby when either end of the shoe is in contact with the pipe, the chain at such end will swing clear of the shoe, while the chain at the other end will 115 be carried away from the pipe and tightened by the cam or rocking effect of the shoe upon it.

5. In a pipe wrench comprising a head, 120 handle and chain, a pipe gripping shoe on the underside of the head extending an equal distance from the center of the head each way, both ends of said shoe being rounded symmetrically with pipe gripping teeth on the underside, the upper side of said shoe 125 having a transverse boss with shoulders fitting within a recess on the underside of said head to prevent said shoe from slipping endwise, means for holding said shoe to the wrench head, a chain fastened to the handle 130

end of the head and extending around said shoe, and means for adjustably attaching the chain to the opposite end of the head in such manner that either end of the chain will be
5 tightened by that end of the shoe not in contact with the pipe.

In testimony, that I claim the foregoing

as my own, I have hereto affixed my signature in the presence of two witnesses.

ADDISON B. CARLL.
